RIVETING TOOL

Morris Brown, San Diego, Calif.

Application June 2, 1944, Serial No. 538,356

10 Claims. (Cl. 78—53.5)

1

The invention relates to bucking tools for riveting.

One object of the invention is to provide an improved manually manipulated bucking tool of the type in which the bucking element which engages the rivets has imparted thereto by a spring-pressed anvil counter blows reactively to the blows imparted to the element through the rivets by the hammer and by which the magnitude of the counter blows and the action of the bucking tool may be varied to proportion the loads on the operators of the bucking tool and the hammer for riveting under different conditions and also for different kinds of work.

Another object of the invention is to provide a hand-manipulated bucking tool with means for damping the vibration of the bucking element to expedite the upsetting of the rivets by counter blows reactively to the blows from the hammer.

Another object of the invention is to provide a bucking tool which is simple in construction and provided with interchangeable bucking elements for different kinds of work.

Other objects of the invention will appear from the detailed description.

The invention consists in the several novel features hereinafter set forth and more particularly defined by claims at the conclusion hereof.

In the drawings:

Fig. 1 is a side elevation of a tool embodying the invention, parts being shown in section.

Fig. 2 is a section taken on line 2—2 of Fig. 1.

Fig. 3 is an end elevation.

Fig. 4 is a view illustrating the bucking tool and the power-operated hammer associated with the work.

Fig. 5 is a side elevation, parts shown in section, with a different form of element for bucking heavy rivets.

Fig. 6 is a face view of the bucking element shown in Fig. 5.

The bucking tool comprises an elongated body 8 which terminates at one end in a handle or grip 9; a bucking element 10 which is provided with an elongated face 10^a adapted to be engaged by a series of rivets *a* in the work *c* and to receive blows through the rivets from a power-operated hammer *b*; a plate-like member 13 welded or otherwise secured on the element and fitting against one side-face of the body for holding the body and element against relative rotation; a pair of anvils 15 symmetrically disposed on the opposite sides of stem 11, engaging an inner face 26 on the element 10 adjacent its ends, respectively, each of which is fixedly secured to

2

a stem 16 which is slidable in a socket 18 in the body 8; coil springs 17 around the stems 16, respectively, for operating the anvils 15 to impart counter blows to the element 10, each spring being confined in a socket 20, and coiled around a stem 16 and interposed between an anvil 15 and a shoulder 19 at the inner end of socket 20; a pair of springs 30 for damping the vibrations of the element 10 and disposed between the stem 11 and the anvils 15 and having their ends held in sockets 31 in body 8 and sockets 32 in the element 10; a nut 22 screw-threaded to the inner end of stem 11 and adapted to be adjusted on said stem to limit the movement of the element 10 away from the body and to vary the normal compression of the springs 30; and a lock-nut 23 and lock-washer 24 for securing the nut 22 in its assigned position on the stem 11. The springs 30 are adapted to press the bucking element against the nuts independently of the anvils, and restrain the element from following the anvils 15 reactively to the hammer blows so that the anvils will impart the full force of their spring imparted blows to the bucking bar in opposition to the hammer blows, and function as damping devices for the vibrations of the bucking element.

The operation of the bucking tool is as follows: The rivets *a* are inserted through the work and the operator of the tool holds the body 8 so that the face 10^a of the element 10 will engage the inner end of the group of rivets and hold the element against the rivet while the power-operated hammer *b*, manipulated by another operator, imparts hammer blows to the preformed head on the rivets. Blows from the hammer will be imparted through the rivet to the spring-pressed element 10 for coacting with the hammer in upsetting the inner end of the rivets. These blows will be transmitted by the element 10 to the anvils 15, causing the latter to rebound from the element against the force of springs 17. These springs operate the anvils 15 to impart counter blows to the bucking element 10. The springs 30 press the element 10 away from the body and toward the rivets independently of the spring-pressed anvils 15 and damp the vibrations of the bucking element 10 to cause the anvils and springs to impart more effective counter blows to the element 10 than when the element is free to vibrate or follow the movements of the anvils. This results in accelerating the upsetting of the heads on the rivets and effects a saving of time in riveting operations.

By providing a single bucking element 10 which is adapted to simultaneously engage a series of

group of rivets, the bucking tool can be held in one position by its operator while the entire group or series of rivets are being successively operated on by the hammer.

In riveting some work, for example aircraft structures, the lack of space makes it desirable to lessen the load on the bucking tool operator in places where it is difficult to resist heavy loads on the bucking tool. It is also desirable to vary the spring-pressure against, and the action of, the bucking element for upsetting rivets of different thickness or sizes or for coaction with hammers of different powers. By adjusting the nut 22 on the stem 11 of the bucking element 10, the force of springs 30 can be varied. For example, if the element 10 is adjusted to increase its distance from the body, the compression of springs 30 and their damping effect will be decreased and the compression of springs 20 will be decreased to decrease their compression and the resistance to the hammer blows on said element will be decreased. When the element 10 is thus adjusted, the bucking tool will be freer to move responsively to the hammer blows with the result that the reactive counter blows of the anvils 15 will be of less force or effect and the load upon the bucking tool operator will be decreased. When the nut 22 is adjusted to move the element 10 toward the body, the compression of springs 20 and 30 will be increased with the result that the bucking element will offer greater resistance to the hammer blows and will receive more powerful counter blows so that the bucking tool operator receives a greater load and the bucking tool effects a greater proportion of the upsetting of the rivets. By means of this adjustment the loads upon the operators for the hammer and the bucking tool may be proportioned as desired, and the action of the bucking tool can be varied for rivets of different weights and hammers of correspondingly greater power.

The mass in the element 10 and in the anvils and the spring-pressure applied to the element 10 are co-related to tend to synchronize the hammer blows and the counter blows. This co-relation has been found to be readily determinable by trial and providing anvils of suitable weight or masses and anvil operating springs and damping springs of suitable magnitude for this synchronization. Adjustment of the nut 22 permits the force of springs 30 to be varied for this purpose.

In Figs. 4 and 5 the bucking element 10^b has affixed to its outer end or integrally formed therewith a cylindrical stud 10^a for engaging a rivet. This element is used more particularly for bucking exceptionally heavy rivets and is fixed to a stem 11^a which is slidably mounted in the body 8^a. The anvils 15, the stems 16, the anvil-operating springs 17, damping-springs 30 disposed in sockets 31 and 32, and the nut 22 for adjusting the force of springs 30, are of the same construction and correlated to the element 10^b in the same manner described in connection with the form of the invention shown in Figs. 1 to 4. Stem 11^a for element 10^b is provided with a cross-pin 34 which extends into a slot 35 for preventing relative rotation of the element 10^b and the body 8^a in lieu of the plate-like extension 13. It is understood that the pin and slot combination could also be provided in the first embodiment for preventing rotation. In this form of the invention the operation of the bucking element 10^b is variable by the adjustment of the nut 22 to vary the normal compression of springs 30 in the man-

ner previously described, and a plurality of damping springs and anvils coact with the single bucking element.

The invention provides a simple and efficient bucking tool for coacting with a power-operated hammer by which a group or series of rivets may be bucked while the tool is held in a single position. It also exemplifies a bucking tool by which the loads imposed upon the operators for the bucking tool and for the hammer may be proportioned as desired and for varying the action of the bucking element for rivets of different sizes or weights. It also exemplifies a tool in which a single bucking element guided in a single body provided with a handle is acted upon by a plurality of spring-pressed anvils. It also exemplifies a bucking tool which is provided with a plurality of devices for damping vibrations of a bucking element which is carried by a portable body.

The invention is not to be understood as restricted to the details set forth, since these may be modified within the scope of the appended claims without departing from the spirit and scope of the invention.

Having thus described the invention, what I claim as new and desire to secure by Letters Patent is:

1. A bucking tool for coacting with a power hammer comprising: a portable body, a bucking element provided with a face for engaging a plurality of rivets and receiving impact blows from the hammer through the rivets, a stem centrally disposed on and secured to the element and slidably mounted in the body, a plurality of spring-pressed anvils provided with stems slidably mounted in the body at the sides of the stem on the element, springs in the body and around the stem on the anvils, for imparting to the element counter blows reactively to the blows received through the rivets from the hammer, a plurality of resilient devices between the element and the body, for damping the vibration of the element, disposed between the stem on the element and the anvils, and means on the stem on the element for adjusting the normal compression of the resilient devices and the range of movement of the element relatively to the body.

2. A bucking tool for coacting with a power hammer comprising: a portable body, a bucking element provided with a face for engaging a rivet and receiving impact blows from the hammer through the rivets, a stem centrally disposed on and secured to the element and slidably mounted in the body, a pin means carried by said stem and movable in a slot in said portable body to prevent rotation of said stem, a plurality of spring-pressed anvils provided with stems slidably mounted in the body at the sides of the stem on the element, springs in the body and around the stems on the anvils, for imparting to the element counter blows reactively to the blows received through the rivets from the hammer, and a plurality of resilient devices between the element and the body, for damping the vibration of the element, disposed between the stem on the element and the anvils.

3. A bucking tool for co-acting with a power hammer, comprising: a portable body, means for providing a hand-hold on said body, a bucking element provided with a face for engaging a rivet and receiving impact blows from the hammer through the rivet and with a stem mounted for rectilinear sliding movement in said body, a plurality of anvil members, each provided with a stem rectilinearly slidably in the body, the

stems of the anvil members being disposed at opposite sides of the stem of the bucking element, a plurality of spring-means in the body, acting on the anvil members respectively, for imparting to the bucking element counter-blows reactive to the blows received through the rivets from the hammer, and means between the bucking element stem and the body for adjusting the normal compression of the springs acting on the anvil members.

4. A bucking tool for co-acting with a power hammer, comprising: a portable body, means for providing a hand-hold on said body, a bucking element provided with a face for engaging a rivet and receiving impact blows from the hammer through the rivet and with a stem mounted for rectilinear sliding movement in said body, a plurality of anvil members, each provided with a stem rectilinearly slidable in the body, the stems of the anvil members being disposed at opposite sides of and parallel with the stem of the bucking element, a plurality of spring means in the body, acting on the anvil members respectively, for imparting to the bucking element counter-blows reactive to the blows received through the rivets from the hammer, and means between the bucking element stem and the body for adjusting the normal compression of the springs acting on the anvil members.

5. A bucking tool for co-acting with a power hammer, comprising: a portable body, means for providing a hand-hold on said body, a bucking element provided with a face for engaging a rivet and receiving impact blows from the hammer through the rivet and with a stem extending longitudinally through, and mounted for rectilinear sliding movement in, said body, a plurality of anvil members, each provided with a stem rectilinearly slidable in the body, the stems of the anvil members being disposed at opposite sides of and parallel to the stem of the bucking element, a plurality of spring-means in the body acting on the anvil members respectively, for imparting to the bucking element counter-blows reactive to the blows received through the rivets from the hammer, and means between the inner end of the bucking element stem and the body for adjusting the normal compression of the spring-means acting on the anvil members.

6. A bucking tool for co-acting with a power hammer, comprising: a portable body, means for providing a hand-hold on said body, a bucking element provided with a face for engaging a rivet and receiving impact blows from the hammer through the rivet and with a stem extending longitudinally through, and mounted for rectilinear sliding movement in, said body, a plurality of anvil members, each provided with a stem rectilinearly slidable in the body, the stems of the anvil members being disposed at opposite sides of and parallel to the stem of the bucking element, a plurality of spring-means in the body acting on the anvil members respectively, for imparting to the bucking element counter-blows reactive to the blows received through the rivets from the hammer, and screw-means between the bucking element stem and the body, for adjusting the normal compression of the spring-means acting on the anvil members.

7. A bucking tool for co-acting with a power hammer, comprising: a portable body, means for providing a hand-hold on said body, a bucking element provided with a face for engaging a rivet and receiving impact blows from the hammer through the rivet and with a stem extending

longitudinally through, and mounted for rectilinear sliding movement, and having its inner end extended outside of said body, a plurality of anvil members each provided with a stem rectilinearly

5 slidable in the body, the stems of the anvil members being disposed at opposite sides of and parallel to the stem of the bucking element, a plurality of spring-means in the body acting on the anvil members respectively, for imparting to 10 the bucking element counter-blows reactive to the blows received through the rivets from the hammer, and means between the end of the bucking element stem outside of the body and the body, for adjusting the normal compression of the 15 springs acting on the anvil members.

8. A bucking tool for co-acting with a power hammer, comprising: a portable body, means for providing a hand-hold on said body, a bucking element provided with a face for engaging a rivet and receiving impact blows from the hammer

20 through the rivet and with a stem extending longitudinally through, and mounted for rectilinear sliding movement in, said body, a plurality of anvil members, each provided with a stem rectilinearly slidable in the body, the stems of the anvil members being disposed at opposite sides of and parallel to the stem of the bucking element, a plurality of spring-means in the body acting on the anvil members respectively, for im-

25 parting to the bucking element counter-blows reactive to the blows received through the rivets from the hammer, a plurality of springs at the sides of the stem of the element and between the element and the body, for damping the vibrations of the bucking element, and means between one end of the bucking element stem and the body for adjusting the normal compression of the spring-means acting on the anvil members, and the damping-springs.

30 9. A bucking tool for co-acting with a power hammer, comprising: a portable body, means for providing a hand-hold on said body, a bucking element provided with a face for engaging a rivet and receiving impact blows from the hammer through the rivet and with a stem mounted for rectilinearly sliding movement in said body, a plurality of anvil members each provided with a stem rectilinearly slidable in the body, the stems of the anvil members being disposed at the op-

35 posite sides of the stem of the bucking element, spring-means in the body, acting on the anvil members for imparting to the bucking element counter-blows reactive to the blows received through the rivets from the hammer, a plurality of springs for damping the vibrations of the bucking element, the body and elements having confronting recesses at the sides of the bucking-element stem, for retaining said springs, and means for adjusting the normal compression of the 40 spring-means acting on the anvil members.

10. A bucking tool for co-acting with a power hammer, comprising: a portable, substantially flat-sided body having an extension providing a hand-hold on said body, a bucking element pro-

45 vided with a face for engaging a rivet and receiving impact blows from the hammer through the rivet and with a stem mounted for rectilinearly sliding movement in, said body; a plurality of anvil members, each provided with a stem rectilinearly slidable in the body, the stems of the anvil members being disposed at the opposite sides of the stem of the bucking element, a plu-

50 rality of spring-means in the body, acting on the anvil members for imparting to the bucking ele-

ment counter-blows reactive to the blows received through the rivets from the hammer, a plate on the element fitting one side of the body, and means for normally adjusting the normal compression of the spring-means acting on the anvil members. 5
